The ornamental design for a gas appliance ignition module, as shown and described.

DESCRIPTION

FIG. 1 is a top perspective view of a new design for a gas appliance ignition module.

FIG. 2 is a bottom perspective view of FIG. 1.

FIG. 3 is a top plan view of FIG. 1.

FIG. 4 is a bottom view of FIG. 1.

FIG. 5 is a front elevation view of FIG. 1.

FIG. 6 is a rear elevation view of FIG. 1.

FIG. 7 is a left side view of FIG. 1; and,

FIG. 8 is a right side view of FIG. 1.

The gas appliance ignition module is shown broken away in FIGS. 1-6 of the drawing to indicate indeterminate length, it being understood that it has a uniform shape and appearance throughout its length.
